UNITED STATES PATENT OFFICE.

HENRY WEBB HYDE, OF NORTH COHASSET, MASSACHUSETTS, ASSIGNOR TO HYDE ENGINEERING COMPANY, OF BOSTON, MASSACHUSETTS, A CORPORATION OF MASSACHUSETTS.

SPRING SUSPENSION FOR VEHICLES.

Application filed April 23, 1924. Serial No. 708,431.

This invention relates to vehicle spring suspensions of the general type shown and described in my prior application for Letters Patent, filed September 29, 1921, Serial No. 5 504,160, patented January 27, 1925, No. 1,524,437.

As explained in said prior application, the invention therein shown consists primarily in providing the vehicle with longitudinal 10 springs or spring reaches connected at their ends, either directly or indirectly, with the axles, and in supporting the body on the spring reaches intermediate the ends of the latter in such a manner as to permit said body to rock freely, with respect to and 15 independently of the reaches, upon a horizontal, transverse axis, so that tilting or rocking of the reaches, caused by a vertical movement of either the front or rear wheels 20 and the axle carried thereby, will not be transmitted to the body and will not tend to tip or pitch the same, said body being permitted, by rocking about its axis with respect to the reaches, to maintain its substantially 25 horizontal position, its only movement being a slight vertical one in a substantially rectilinear direction.

In another application, filed August 24, 1923, Serial No. 659,096, is shown and described a form of spring suspension of the general type of that above referred to wherein vertical movement of an axle at either end of the vehicle is accompanied by the application of balanced vertical forces to 35 the body at both sides of the center of gravity thereof, said body being therefore held against pitching under the influence of vertical shocks resulting in a rocking of the reaches in either direction, and wherein 40 balancing springs are so arranged as to provide spring supports for the body between the end thereof and the rocking or pivotal axis, so as further to stabilize the body and also, to a certain degree, to counteract the forces tending to move the body 45 vertically in a rectilinear direction, thereby resisting movement of the body of any character, and providing for a quite complete absorption of the road shocks by the resilient 50 portions of the suspension.

The present invention has for its object to provide a modification of the construction shown in my application last above referred to, in which modification the inter-

mediate spring supports for the body are afforded by the spring reaches themselves instead of by the use of special balancing springs.

This and other objects of the invention, together with means whereby the same may be carried into effect, will best be understood from the following description of one form or embodiment thereof illustrated in the accompanying drawings, in which:

Fig. 1 is a side elevation of a suspension 65 constructed in accordance with the invention.

Fig. 2 is a plan view thereof, the body frame being partly broken away in order to show the parts of the suspension beneath 70 the same.

The principle of operation of a spring suspension of the general type of that to which the present case relates is fully explained in my prior application, Serial No. 75 504,160. For the purposes of the present description this principle may be briefly outlined as follows:

In the ordinary vehicle, whether provided with elliptical, semi-elliptical, or cantilever springs, the springs are, in effect, rigidly secured to the body or frame, and any shock or blow on a wheel, due to unevenness in the road, which causes the wheel to rise or fall suddenly, is communicated directly to 85 the body substantially at the ends of the latter so as to produce the maximum gyroscopic effect.

In the type of spring suspension to which the present invention relates, on the contrary, if the front wheel, for example, be raised, owing to an unevenness in the road, the tendency is for the spring reach to turn about the pivot afforded by the rocker on which the body is supported, but not to rock 95 the body. It thus tends to swing the rear end of the reach and rear axle downward about the pivot, so that the chief effect of the blow is absorbed by the rear spring and pneumatic tire on the rear wheel. Likewise, 100 when the rear wheel goes over an obstruction or drops into a hole, the front spring member and front wheel receive the major part of the reaction and the body is affected relatively little. In any event, any 105 force, or the resultant of such forces as may be transmitted to the body as a result of the rocking of the reaches, is applied to the

body substantially at the center of gravity thereof, so that there is no gyratory force acting upon the body eccentric to its center of gravity. The effect on the body is merely to lift the pivot, and consequently the body, vertically to a slight extent, and not to rock said body from front to back, so that the body is not given any pitching motion. The action described is permitted by the pivotal or rocking connection between the body and the spring reaches. If there were a rigid connection at this point, the blow would give the body an entirely different movement and would not be absorbed by the opposite end of the spring reach.

Referring now to the drawings, there is shown therein a pair of spring reaches to which the body frame 10 is connected by means of coaxial pivots 11 interposed between brackets 12 and 13 secured to said body and reaches respectively, the axis of said pivots being disposed forward of the center of gravity of the body, and the forward end of said body being free. Each of the spring reaches is composed of a substantially rigid beam 14 having leaf spring extensions 15 and 16 at its forward and rear ends respectively. The forward spring extensions 15 are bolted or otherwise secured at their forward ends to the front axle 17 of the vehicle. Supported intermediate their ends by hangers 18 from the rear axle 19 of the vehicle are substantially semi-elliptical springs 20 connected at their outer or rear ends by shackles 21 with the rear end of the body frame 10. At their inner or forward ends, the springs 20 are pivotally connected to brackets 22 secured to the spring extensions 16 of the respective reaches. The brackets 22 are secured to the spring extensions 16 at points between the beams 14 and the outer or rear ends of said extensions, which are continued beyond said brackets 22 and connected by shackles 23 with the body frame 10 rearwardly of the center of gravity of the latter.

When the rear axle 19 is raised, upward forces are applied to the body at opposite sides of the center of gravity thereof through the pivots 11 and shackles 21, the moments of which forces are balanced about the center of gravity so as not to rock the body, as more fully explained in application Serial No. 504,160 above referred to. When the front axle 17 is raised, the forward end of the body is lifted by the pivots 11, the rear ends of the reaches being at the same time swung downwardly about said pivots, thereby, through the springs 20 acting as levers fulcrumed on the axles 20, exerting an upward force upon the rear end of the body also tending to prevent pitching thereof, as more fully explained in another application, filed May 28, 1923, Serial No. 641,933. The portions of the spring extensions 16 between

the brackets 22 and shackles 23 act as balancing springs to compensate for varying loads in the tonneau, the principle being the same as in the construction shown and described in application Serial No. 641,933, 70 above referred to, wherein quarter elliptic springs fastened to the frame act at the pivotal points between the spring extensions of the reaches and the springs supported by the axle. The relative length of the two halves of each of the springs 20 is so proportioned, in relation to the length of that portion of the corresponding spring reach between the fulcrum 11 and bracket 22, that the end of the spring extension 16 exerts a 75 downward force on the body when the tonneau is light and an upward force on the body when the tonneau is fully loaded, thus compensating for the variation in load. The parts are so designed that the moments of 80 the vertical forces transmitted to the body through the connections 11, 21 and 23 are substantially balanced about the center of gravity of the body, while the rear ends of the spring extensions 16 of the reaches beyond the shackles 22 comprise only one or 85 two leaves and therefore constitute relatively light springs, so that the additional connections 23 between the body and the reaches do not in any way interfere with the 90 operation of the suspension in accordance with the general principles first above outlined.

In this specification, the phrase "spring reaches" is employed as a comprehensive term to denote longitudinal members through which the body is supported from the axles, and composed wholly or in part of springs. The term, therefore, is to be taken as including a unitary or continuous spring as well as a reach composed of a substantially rigid beam to the ends of which are attached springs. It will be understood that when the spring reach is constructed as last described, and as herein shown, the connection between the beam and the springs is a rigid one in the sense that there is no pivotal or other movable connection at this point.

The words "rear," "front," and similar expressions are herein used as convenient illustrative terms, it being obvious that, although the construction shown is preferred for most purposes, the suspension might be oppositely disposed, the pivotal connection between the body and the reaches being in the rear instead of in front of the center of gravity of the body, and the other parts being correspondingly arranged. These and other modifications of the construction shown will, however, be readily apparent to those skilled in the art without further description in detail.

Having thus described my invention, I claim:

In a vehicle having a body and axles, a 130

spring suspension comprising a pair of spring reaches each connected with both of said axles, and a connection between said reaches and the body upon which the latter is free to rock with respect to the former, said suspension including a spring member carrying said connection intermediate its ends and connected at one end to the body, and a semi-elliptical spring supported by an axle and connected at its outer end to the body and at its inner end to said spring member.

In testimony whereof I affix my signature.

HENRY WEBB HYDE.
